UNITED STATES PATENT OFFICE.

WALTER A. DORSEY, OF COLUMBUS, OHIO, ASSIGNOR TO THE BONNEY-FLOYD COMPANY,
OF COLUMBUS, OHIO, A CORPORATION OF OHIO.

COAL-MINE CAR.

1,305,076.

Specification of Letters Patent. Patented May 27, 1919.

Application filed June 29, 1915. Serial No. 37,086.

To all whom it may concern:

Be it known that I, WALTER A. DORSEY, a citizen of the United States, residing at Columbus, in the county of Franklin and State of Ohio, have invented certain new and useful Improvements in Coal-Mine Cars, of which the following is a specification, reference being had therein to the accompanying drawing.

10 This invention relates to improvements in the cars used for the haulage of coal from mines.

Such cars are subjected to exceedingly severe usage. The grades in the mines are 15 frequently steep and the cars are subjected first to severe pulling strains as they go up these grades, and then to severe pressure. And the grades are laid on short radii so that the cars and in fact entire trains are

20 frequently thrown from the tracks.

In consequence of these hard conditions breakages of parts and the destruction of cars are frequent.

When they have been built up on the plans 25 heretofore followed a breakage, even though it be of one of the minor parts, will frequently require that the entire car be set aside to await the repair of such broken part. Blacksmith and machine shops are required 30 at the mouths of the coal mines to meet the large amount of labor incident to keeping the cars in repair. Here they, often in large numbers, must await their turn to be taken to pieces and reconstructed, even in cases 35 where only a minor part has been damaged or broken. Much of the expense incident to the operation of these coal mines is that incident to the tying up of the cars that are broken or impaired, or worn out, and frequently, just at the time when there is urgent 40 demand for numerous cars at a coal plant there will be a serious hindrance to the output because of those that are tied up for shop work.

The object of this invention is to provide 50 a car for use in coal mines which, first, will be so constructed that those parts which are subjected to the severest pulling and pressure strains and to lateral torsion can be made of metal and exceedingly strong, but light; and so that the detailed parts will be so related to each other and to the entirety that each of a number can be built up of composite unitary elements which can

be made as separate elements at the factory 55 and can be kept in stock at the mines, any one of which elements can be quickly substituted for a corresponding impaired or broken one. Skilled mechanics are not needed to repair a car, the only labor required being the detaching of a few bolts, inserting a new unitary element, and replacing the bolts.

The car which I have devised is illustrated in the drawings. 65

Figure 1 is a side elevation of a car embodying my improvements.

Fig. 2 is a top plan view of the base frame.

Fig. 3 is a plan view of the base frame with the flooring at one end in place and 70 showing the manner of mounting upon the truck wheels together with the bracket devices.

Fig. 4 is a side or edge view of the base frame element. 75

Fig. 5 is an end view of the same.

Fig. 6 is a side or face view of the central bracket of one of the side walls.

Fig. 7 is an edge view of the part in Fig. 6.

Fig. 8 is an end elevation of one of the 80 rear corner brackets of the body.

Fig. 9 is a face view of the parts shown in Fig. 8.

Fig. 10 is a side and Fig. 11 is an edge view of one of the front brackets. 85

Fig. 12 is a rear end view of the car.

Fig. 13 is a view from the front or gate end.

Fig. 14 is a perspective showing the several elements of the car detached from each other. 90

The base frame which receives all of the pulling and pressure strains is indicated as an entirety by 1. It is formed as a rectangular unitary steel casting, and with it are 95 formed, integrally, the bumpers 2 or draw-bars, coupling sockets 3, seats 4 for the axle boxes, sockets 5 for the center brackets of the side wall elements, and end sockets 6 and 6^a to receive the front and rear brackets, and 100 bearings 7 for the brake shaft.

Parts of this base frame are the strong steel sills 8, extending from end to end of the car, and also the integral cross girt bars 10, the aforesaid draw bars or bumpers at 105 2 connecting the sills at the ends. These sills and girts are disposed in relation to each other and to the lines of strain and of

torsion exerted upon the car in such way that it is practically impossible, under any of the ordinary stresses to which it is subjected to distort the frame or break it.

5 The side sills 8 are formed with vertical flanges 11 and inwardly extending horizontal flanges 12. The upper surfaces of the flanges 12 coincide with the surfaces of the girts 10 and of the flanges 13 of the 10 end cross bars. And upon the surfaces of these flanges and girts are laid the heavy planks 9 which form the floor of the car, the upper surfaces of the planks being approximately flush with the upper edges of 15 the vertical flanges at the front and rear ends of the bottom casting.

Heretofore in coal mining cars the base frames have been made of timbers secured together in one way or another, and consequently those parts of the cars are liable to breakage from severe strains and twistings, the wooden timbers and planks which receive the strains not being successfully held in position. This is obviated in the 25 present construction, as all of the parts that are in the plane of the lines of draft, are, as above described, formed of metal in one integral casting in the form of a frame extending continuously from end to end 30 and from side to side of the car, with its tension bars and reinforcements so disposed as to reduce to a minimum the amount of metal required, and at the same time present that metal to the lines of strain and 35 compression and transverse torsion.

This frame casting is formed with horizontally expanded plate-like parts at 13 to give extended and firm support to the axle bearings. 14 are the metal loops forming 40 the top walls of the sockets 3 for the couplers, these loops being also cast solid with the base frame. 15 is an aperture in the loop and 16 a registering aperture in the integral frame below it for receiving the 45 coupling pin 16a.

The side walls and end walls are formed as separate integers ready to be attached to or detached from the base structure. Each side wall is formed with an upper 50 outer part 17, a lower inner part 19, and an intermediate inclined part 18. At each rear corner of the car there is a bracket indicated as an entirety by 20, comprising an upper vertical bar 26, an inner bottom bar 27, and an inclined intermediate bar 28, these being arranged to provide a flange 21 extending lengthwise of the car and a flange 22 extending transversely and all of the said parts 21, 22, 26, 27, and 28 are cast 55 integrally together. At the lower ends of these brackets there are integral extensions or tenons 24 each provided with a lock-receiving aperture 25. In the flange 21 are apertures 29, and in flange 22 are apertures 30.

At the front end of the car there are two corner brackets, indicated by 31, each comprising an outer top bar 32, an inner bottom bar 33 and an intermediate inclined bar 34, and having a vertical extension 35 70 at the top with a hinge bearing aperture 36. At the lower end there is an extension or tenon 38 with a lock-receiving aperture 39. At 37 there are apertures in the bracket for bolts. 75

There are two center brackets. Each is indicated by 70 and has an upper outer bar 71, a lower inner bar 72 and an intermediate inclined part 73, the latter being formed with horizontal extensions 74. At the lower 80 end of this bracket there is an extension or tenon 75 with a lock-receiving aperture 76. The three brackets of each side section are connected together by planks 31^a, 31^b, 31^c, each being bolted at its rear end in 85 the angle formed by the flanges 21 and 22 of the rear bracket and bearing snugly against the outer flange 21 and against the parts 71 and 32 of the other brackets. Each plank 31^b is secured to the intermediate or 90 inclined parts of the brackets in a similar manner; and the lower plank 31^c is secured to the lower parts of the brackets.

It will be seen that the brackets 20, 31 and 70, respectively, have inner lower vertical bars and upper outer vertical bars. Thus, for example, the bracket 31 has an inner lower vertical bar at 33, and an upper outer bar at 32; and so in respect to the other brackets. That is to say, the upper vertical bars 26, 32 and 71 lie in a vertical plane parallel to the longitudinal vertical planes of the car, which is outside of the vertical longitudinal plane of the inner lower bars, of the brackets, 27, 33 and 72. 105 It will also be seen that the plank or side wall part 17 supported in the brackets is in vertical longitudinal planes outside of the vertical longitudinal planes of the lower inner plank 19. 110

The rear wall of the car is indicated by 40, comprising a narrow section 42 and an upper tapering wider part 41. This is bolted firmly in place against the transverse flanges 22 of the rear brackets. Its 115 upper edge is reinforced and firmly held by a cross bar 44 which is at its ends secured by two of the bolts that pass through the bracket flanges.

The bottom part of this end wall is snugly 120 flush with the top surface of the plates or planks 9 secured to the base frame.

At the front end of the car there is a swinging gate, indicated as an entirety by 45, which is formed with an upper wider 125 part 46 and a bottom narrower part 47. These parts are composed of plates or planks which are secured to vertical brace bars 48. These extend from the bottom of the gate to lines above the top, as at 49, and 130

are provided with hinge eyes 50. These brace bars also have bearings 51 near their lower ends. 52 is a hinge rod which is mounted in the bearing apertures 36 in the 5 aforesaid extensions 35 of the front brackets. Upon this rod are fitted the hinge loops 50. To hold the gate firmly in position when elevated, spacer tubes 53 are interposed between the hinges 50 and the front 10 corner brackets. 54 is a rock shaft for carrying and operating the gate lock. It has a latch dog 55 adapted to engage with the latch pin 56 carried by one of the front body brackets. 57 is a lever secured to the shaft 15 54 and carrying a latch dog 58 adapted to engage with a companion latch part 58^a on the gate.

59, 59 indicate the axles which are mounted in the bearings 59^a secured in the bearing 20 seats on the under sides of the base frame. 60, 60 are the car wheels carried by the axles. 61 is a brake block mounted in the longitudinal planes of the wheel rims and having concave surfaces at 62 for engaging with 25 the wheels. Each brake block is held in proper vertical lines by means of guide rods 63 carried by the central bracket 70 and by the guide rods and guide plate 64. 65 is a lever connected to the rocking brake 30 shaft 66 mounted in the bearings 7 that are integral with the base frame. The short arm of the lever 65 is connected to the brake blocks by means of an arm 68. 77 is a ratchet bar bolted to the front corner bracket 35 with which the lever engages to hold the brakes in their adjusted positions.

The devices for locking the tongues or tenons 25, 75 and 38 in the sockets 5, 6, and 6^a may be bolts or pins held by cotter keys 40 so as to be readily detachable.

From the above description it will be seen that I provide a mine car having a base frame, sides and ends which are separately constructed unitary integers, any one of 45 which can be quickly removed, and for any one of which another can be readily substituted without requiring skilled labor or work in a shop. Yet the parts are so constructed and related to each other that when 50 assembled and fastened together in the way described, a car of much greater strength is provided than is the case with any of the coal mine cars now in use.

The several composite elements, which 55 when assembled form a car, are separately built up at the factory from the detailed parts which are secured together to provide these unitary structures. That is to say, the parts of each side wall are secured together to constitute the composite elements 60 shown in Fig. 14, this being true also of the rear end wall, the front end wall, of the frame and axles, and the wheels, which are shipped to the mines as separate units, or in 65 sets in "knock-down" condition. When they

reach the mines they are assembled by labor of the simplest form, and are at once ready for use.

In case of breakage of, or other accident to, any one of these composite elements in 70 a car, another similar element can be taken out of the stock and substituted without any time being lost either for labor at the shops or in waiting for its turn for repairing, nor is skilled labor required for the rebuilding. 75

The cast steel frame and its attachments may be regarded as practically indestructible, and notwithstanding accidents or breakages of the other parts, it is always ready for having new attachment units 80 separately fastened to it.

The brake blocks are flexibly carried by and held to the base frame, which latter, in conjunction with the lever 65 and the car wheels, hold them in position, even though 85 the side wall sections are removed. And when a side wall is replaced the brake-guide elements thereon immediately fit into the companion guide element on the brake and thereafter the detachable side wall furnishes 90 the bracing and guiding for the brake block, which is firmly held thereafter in true position.

The sockets 5, 6, 6^a are prolonged vertically so as to give elongated bracing for 95 the tenons or tongues on the brackets.

What I claim is:

1. A mine car having a cast frame extending integrally from end to end and from side to side of the car and cast with the relatively elongated, vertical sockets 5, 6, 6^a, the expanded bearing plates 13, the coupling loops 14, the detachable side walls each formed of three brackets 20, 31 and 70, each bracket having a tongue fitting and adapted 100 to be detachably locked in one of the said sockets and the rear brackets being cast with transversely extending flanges 22, the rear end wall 40 detachably bolted to said flanges, the detachable swinging front gate wall, the 110 hinge rod mounted in the upper ends of the front body brackets from which the front gate wall is pivotally suspended, and the gate locking means carried by the front gate wall and one of the front brackets. 115

2. A coal mine car having in combination the cast steel main frame extending integrally from end to end and from side to side of the car and having the bumpers, the coupling loops 14, the vertically disposed, relatively elongated sockets 5, 6, 6^a, the brake shaft bearings 7, the expanded axle bearing plates 13, 13, and the cross girts 10 all cast integrally together with the frame, the detachable side wall sections each formed with 120 three brackets, respectively at the ends and at the center of a section, each bracket having a tongue detachably fitting and locked in one of said sockets and having two vertically 125 extending integral arms together with an in- 130

- clined intermediate arm, the central bracket being formed with a brake guide element, and the rear brackets being formed with the transverse apertured flanges 22, the separably formed rear wall 40 detachably secured to the said flanges, the binding and bracing bar 44 bolted to said flanges, the separably formed gate wall hinged to the extensions 35 of the front brackets and normally held by 5 a manually controlled lock to one of the front brackets, the brake blocks movably mounted on the cast base frame and having guides fitted to the guides on the center bracket, and the brake lever mounted on the 10 base frame.
3. In a coal mine car having in combination the cast steel main frame extending from end to end and from side to side of the car and having the side sills 8 with vertical 15 and horizontal flanges, the cross bumper bars with vertical and horizontal flanges, the cross girts 10, the expanded axle bearing plates 13, 13, the vertically extended sockets 5, 6, 6^a, and the brake shaft bearing 20 7 all cast integrally as parts of the said frame, the bodily detachable side wall sections each formed of a series of vertical and inclined plates or planks, and three brackets which are respectively at the center 25 and at the ends of the wall section, each bracket having a tongue detachably fitting and locked in one of said sockets, the rear brackets having transversely disposed flanges and longitudinal flanges secured to said plates or planks and the front brackets having at their upper ends upwardly extending projections, the bodily detachable rear end wall separably secured to 30 said transverse flanges and bracing together 35 the side wall sections, the bodily detachable swinging front gate end wall section, the hinging and suspending rod for the last wall section, the shaft mounted in the said bearings 7, the brake blocks supported on said 40 shaft, and the brake guides carried by one of the side brackets.
4. For a mine car having a relatively nar-

row floor base, provided with upwardly opening sockets, and an upward and outward flared load chamber, the herein-described separable unitary wall sections, each having an inner vertical wall plank, an outer vertical wall plank, and an intervening inclined wall plank, and, for securing its planks in position, having a front bracket 50 31, a rear bracket 20, and a central bracket 70, respectively formed integrally with a central inclined bar, an inner vertical lower bar, and an outer vertical upper bar, the lower ends of all the brackets having similar 55 tenons for engaging with the aforesaid sockets on the floor base, the forward bracket 31 having an upward extension for pivotally supporting the door hinge, and the rear bracket 20 having integral transverse flanges 60 for the rigid attachment of the tapering rear wall.

5. For a mine car having a relatively narrow floor base, provided with upwardly opening sockets, and an upward and outward flared load chamber, the herein-described wall sections detachably secured rigidly to the floor base, each having a front bracket 31, which is formed integrally with an inner lower vertical bar 33 terminating 70 in a tenon 38, an upper outer vertical bar terminating in a hinge-supporting arm 35, and an intermediate inclined bar 34, and each having a rear bracket 20 with an inner lower vertical bar and an outer upper 75 vertical bar integral with an intervening inclined bar, and also a central bracket 70 formed with inner and outer vertical bars and an intervening inclined bar, said central bracket having guiding and supporting 80 devices for a brake shoe, substantially as set forth.

In testimony whereof, I affix my signature, in presence of two witnesses.

WALTER A. DORSEY.
